UNITED STATES PATENT OFFICE

JOHN LOGIE BAIRD, OF LONDON, ENGLAND, ASSIGNOR TO TELEVISION LIMITED, OF LONDON, ENGLAND, A BRITISH COMPANY

FACSIMILE TELEGRAPHY

Application filed June 7, 1928, Serial No. 283,695, and in Great Britain June 20, 1927.

This invention is for improvements in or relating to facsimile telegraphy, that is to say, the reproduction by telegraphic means of a drawing, photograph, document or the like. The word "drawing" will be used in this specification to indicate the object whereof a facsimile is to be reproduced at the receiving station.

This invention comprises in facsimile telegraphy, a method of transmission wherein the drawing is cut into a series of strips, the strips are arranged (for example joined) end-to-end to form a continuous band, and the band is used in transmitting apparatus wherein the exploration is effected as to one direction by the longitudinal movement of the band itself and as to the other direction by a traversal laterally of the length of the band.

This invention also comprises a method of reception in facsimile telegraphy wherein the picture is received as a continuous band, consisting in cutting the received band in appropriate sections and assembling the sections side-by-side to reconstitute the complete picture.

The construction of the continuous band may be effected in various ways, either by securing the various strips of the drawing directly together, or by mounting them upon a perforated strip such as a kinematograph film. The strips may be joined end-to-end or a small gap may be left between successive portions.

The exploring mechanism of the transmitter may be of any desired type which gives exploration in a direction transverse to the length of the band passing through the apparatus, the movement of the band itself providing the exploring movement at right angles to the first-mentioned movement.

At the receiving station a photographic film or other light-sensitive medium in the form of a long band is used to receive the signals. It is moved longitudinally in synchronism with the movement of the band at the transmitting station, and a lateral exploring device of any desired type is also operated synchronously with the lateral exploration at the transmitting station. A

light controlled by the incoming signals is projected upon the photographic film, the intensity of the light being controlled in the usual manner so as to produce light and shade effects corresponding to those of the drawing being transmitted.

In the accompanying drawings:—

Figure 1 is a perspective view of a transmitting apparatus which may be employed in carrying out a method of transmission according to the present invention;

Figure 2 is a side elevation of the apparatus, shown in Figure 1; and

Figure 3 is a plan of the apparatus shown in Figure 1.

In the apparatus shown in the drawings, a series of lenses 2 (Figure 1) is mounted in a circle on a disc 4 which revolves in front of the moving band 6 which, as hereinbefore mentioned, is formed from a series of strips, arranged end-to-end, cut from the drawing which is to be transmitted. The lenses 2 in their operative position are moved by rotation of the disc 4 transversely of the length of the band 6 and in so moving, traverse an image of that portion of the band which at any instant is illuminated, as presently will be described, across a light-sensitive cell 8, for instance a selenium cell. The band is moved lengthwise, by means to be described, its movement being slow compared with the lateral traversing movement, so that, in effect, the band is divided into transverse lines which are successively traversed over the cell 8.

The means for moving the band lengthwise comprise a pair of reels 10 and 12, the reel 10 being rotated to wind the band upon it and to unwind the band from the reel 12. The reel 10 has fast upon its shaft a worm-wheel 14 driven by a worm 16 on a shaft 18 which is connected by a clutch 20 to the shaft 22 of an electric motor 24 (Figures 2 and 3). The disc 4 is fast upon the shaft 22 and is thus also driven by the motor 24. Between the two reels 10 and 12, there is a guide 26 for the band in which guide an opening 28 (Figure 3) is formed so as to allow light from two lamps 30 to fall upon the band. Each lamp is provided with a concave mirror 32 103

for concentrating the light from the lamp upon the band, the direction of each beam of light being at an angle of about 45° to the length of the band, as shown in Figure 3, so as to secure an even illumination of the portion of the band exposed by the opening 28. It will be seen from an inspection of Figure 3 that the parts are so arranged that a right line passing through the cell 8 and the opening 28 is cut by the centres of the lenses 2 as they sweep past the opening 28 in the rotation of the disc 4. The clutch 20 connecting the shafts 18 and 22 is normally maintained closed by means of a spring 34, but can be opened when the occasion arises by a hand-lever 36 to disconnect the motor 24 from the band-driving means.

Alternatively, a single fixed lens may be used to project an image of the band on to a rotating radially-slotted disc which moves in front of a fixed slot, which lies transversely of the film, this arrangement projecting successive points of the band on to the cell. Also, a disc with a series of holes around its circumference, or a revolving polyhedron mirror, may be used.

Instead of causing the image to traverse the cell, the lateral traversal may be obtained by moving a spot of light across the band, somewhat in the manner described in British patent specification No. 269,658 (applicants J. L. Baird and Television Limited). It will be appreciated, however, that the spot of light has merely to traverse the band in one direction instead of having two component movements at right-angles to one another. This method has the advantage that a very intense light may be used without damaging the band. The traversal of this spot of light may be effected in any convenient manner, as by revolving lenses, shutters, mirrors, prisms or the like, and the arrangement may be such as to operate by means of light reflected from the surface of the band if the picture be opaque, or by light transmitted through it if it be transparent.

The apparatus at the receiving station may be of the same general character as that of the transmitting apparatus illustrated herein. That is to say, it will comprise means for moving lengthwise a band of photographic film or the like, suitably shielded from light except for an opening in the shield, like the opening 28 shown in Figure 3. Light from a suitable source situated in front of the opening in the shield and controlled by the incoming signals from the transmitting apparatus will fall upon the portion of the film exposed at the said opening, exploration being effected by a disc with lenses similar to the disc 4 and lenses 2 and similarly arranged in relation to the opening and to the light-source as are the disc 4 and lenses 2 in relation to the opening 28 and cell 8. The control of the light may be effected di-

rectly on a glow-discharge lamp, or by means of a magnetically-controlled shutter or equivalent device with any other suitable source of light. The traversal of the light over the photographic film may be effected in any desired manner, by means of revolving lenses as just mentioned, or by shutters, mirrors or prisms, it being necessary only that synchronism should be maintained between the transmitting and receiving stations; this may be effected by means of a special synchronizing signal transmitted at regular intervals, say at the end of each strip into which the original drawing is divided.

It will be appreciated that by using the present invention, a drawing of any size can be transmitted by a single apparatus, since it can be divided into strips of a standard width to suit the apparatus, and any length of these strips can be transmitted; the band at the receiving station is cut into appropriate lengths corresponding to the original strips (these being indicated for example by the synchronizing signal) and the various portions assembled together side-by-side to reconstitute the original drawing and provide a facsimile thereof.

Having now particularly described and ascertained the nature of my said invention and in what manner the same is to be performed, I declare that what I claim is:—

1. A method of transmitting pictures which comprises separating the picture into a plurality of parts, arranging the parts in contiguous relation to form a strip, moving the strip in the direction of its length and simultaneously scanning the strip in a direction transverse thereof, and converting the resulting light waves into electrical energy.

2. A method of transmitting pictures from flexible sheets which comprises cutting the sheets to form a series of relatively narrow strips, uniting the strips end to end, moving the flexible band thus formed in the direction of its length, scanning the band transversely thereof, and converting the resulting light waves into electrical energy.

3. A method of transmitting pictures from flexible sheets which comprises cutting the sheets to form a series of relatively narrow strips, uniting the strips end to end, moving the flexible band thus formed in the direction of its length, scanning the band transversely thereof, converting the resulting light waves into electrical energy, reconvert ing the electrical energy into light waves, recording the last named light waves, severing the recorded band to correspond to the first named strips, and assembling the strips to form a completed picture.

In testimony whereof I affix my signature.
JOHN LOGIE BAIRD.
